UNITED STATES PATENT OFFICE.

FRANK SCHUH, OF TRENTON, NEW JERSEY.

FLUSHING APPARATUS.

1,299,789.

Specification of Letters Patent. Patented Apr. 8, 1919.

Application filed September 26, 1917. Serial No. 193,371.

To all whom it may concern:

Be it known that I, FRANK SCHUH, a citizen of the United States, and a resident of Trenton, in the county of Mercer and 5 State of New Jersey, have invented a new and Improved Flushing Apparatus, of which the following is a full, clear, and exact description.

The invention relates to sanitary apparatus such as water closets, sinks, urinals, traps and the like.

The object of the invention is to provide a new and improved flushing apparatus arranged to insure proper emptying of a tank 15 or like receptacle, for flushing purposes through a siphoning action of the contents of the receptacle and a subsequent refilling of the receptacle with water from a water supply. Another object is to dispense with 20 the numerous metallic fixtures liable to corrode and now generally employed, such as supply and flush valves, metallic siphons, overflows, feed and refill pipes, rubber ball valves, metal floats, leather valves and rubber valve seats and the like. Another object is to simplify the construction by using 25 comparatively few parts not liable to get easily out of order, thus insuring long life to the flushing tank.

30 In order to produce the desired result use is made of a tank or similar receptacle of porcelain, glass or other vitreous material, and a siphon within the tank and integral therewith. Use is also made of a combined 35 float and dumping reservoir of a single piece of vitreous material and capable of delivering a proper amount of water to start the siphon.

A practical embodiment of the invention 40 is represented in the accompanying drawings forming a part of this specification, in which similar characters of reference indicate corresponding parts in all the views.

Figure 1 is a sectional front elevation of 45 the flushing apparatus applied to a water closet tank, the section being on the line 1—1 of Fig. 2, and showing the tank and the reservoir filled with water;

Fig. 2 is a plan view of the same with a 50 portion of the siphon shown in section;

Fig. 3 is a sectional front elevation of a portion of the flushing apparatus and showing the combined float and reservoir in tilted position;

55 Fig. 4 is a sectional front elevation of a portion of the flushing apparatus and show-

ing the siphon and the water inlet in section, the section being on the line 4—4 of Fig. 2;

Fig. 5 is a cross section of the flushing 60 apparatus on the line 5—5 of Fig. 1; and

Fig. 6 is an enlarged sectional plan view of the water inlet valve, the section being on the line 6—6 of Fig. 4.

The flushing tank 10 is made of porcelain, 65 glass or other suitable vitreous material and is closed at the top by a suitable cover 11 of the same material. Within the tank is arranged a siphon 12 which forms an integral part of the back and bottom of the 70 tank 10, and this siphon 12 is provided with an inlet leg 13 and an outlet leg 14, preferably made rectangular in cross section and gradually diminishing in size from the entrance end of the inlet leg to the terminal 75 of the outlet leg, as will be readily understood by reference to Fig. 5, to insure a proper siphoning action, as hereinafter more fully explained. The lower end of the inlet leg 13 is provided with an integral foot 15 80 having large entrance openings 16 at the sides and front, and having small apertures 17 in the top, as plainly shown in Fig. 5. It is understood that when the water is siphoned out of the tank and its level reaches 85 the top of the foot 15 then air is sucked into the inlet leg 13 by way of the small apertures 17 to quickly break the siphon action. The lower end of the outlet leg 14 terminates in a foot 20 the top of which extends 90 to the front of the tank 10, and a portion of the top forms the bottom of the foot 16, and the bottom of the foot 20 is formed by the bottom 21 of the tank 10, as plainly shown in Figs. 4 and 5. In the bottom 21 95 is arranged an outlet opening 22 in which is fitted a thimble or bushing 23 engaged by the upper end of the outlet pipe 24 connected with the bowl of the water closet for flushing the same. It is understood that I 100 do not limit myself to this connection between the outlet opening 22 and the bowl of the water closet, as the outlet opening 22 may be connected in any suitable manner with the water closet bowl.

105 Within the upper portion of the tank 10 is arranged a combined float and dumping reservoir 25 made of a single piece of vitreous material such as porcelain, glass and the like. The front and back of the 110 combination float and reservoir 25 are provided with lugs 26 through which extends

- a transverse rod 27 engaging at its ends feet 28 and 29 attached to the front and back of the tank 10. By the arrangement described, the combination float and reservoir 25 is free to swing, as hereinafter more fully explained. The combination float and reservoir 25 is arranged to form a float 30 and a reservoir 31, of which the float 30 serves to return the combination float and reservoir 5 to normal position on the refilling of the tank 10 after the same has been emptied of its contents by the siphon 12. The reservoir 31 is adapted to be filled with water to provide an additional amount of water to be 10 emptied into the tank 10 to raise the level of the water therein to a level above the top of the siphon 12 to start the latter. The reservoir 31 is provided with a bottom, a portion 32 of which is approximately 15 at a right angle to the front, back and end of the reservoir, and another portion 33 of the bottom of the reservoir 31 is inclined upwardly and terminates at its upper end on the top edge of the reservoir. 20 Below this inclined bottom portion 33 is arranged the float 30, the lower portion 34 of which extends below the plane of the straight bottom portion 32 so that this lower bottom portion of the float 30 is submerged 25 while the tank 10 is filled with water, as plainly indicated in Figs. 1 and 3.
- The reservoir 31 is filled with water through a spout 40 extending from a valve casing 41 screwing on the upper end of a water supply pipe 42 extending vertically 30 within a tubular passage 43 forming an integral part of the top and bottom of the tank 10 and of one end of the siphon 12, as plainly indicated in the drawings. The lower end 35 of the water supply pipe 42 extends through an opening 44 in the bottom of the tank 10 and that of the passage 43, and the lower end of the water supply pipe 42 is connected in the usual manner with a suitable source 40 of water supply. A washer 45 and a nut 46 engage the lower end of the water supply pipe 42, and the washer 45 abuts against the under side of the bottom of the tank 10 to make a tight joint of the water supply 45 pipe 42 with the bottom of the tank. The valve casing 41 is provided with a rabbet 47 engaged by a washer 48 of rubber or other suitable material and seated on the top of the passage 43 to form a tight joint between the passage and the valve casing 41. The bottom of the valve casing 41 is provided with openings 49 which connect the interior of the valve casing 41 with the interior of the passage 43. The valve casing 50 41 is provided with a valve seat 50 controlled by a valve 51 mounted to slide up and down in a bearing 52 formed on the top of the valve casing 41. The outer end of the valve 55 51 is provided with an opening 53 through which extends a lever 54 fulcrumed at one end at 55 on a bracket 56 integral with the valve casing 41. The free end of the lever 54 is engaged by a saddle or a fork 60 formed on one end of a lever 61 fulcrumed at 62 on a bracket 63 attached to or forming part of the valve casing 41. The free end of this lever 61 is provided with a socket 64 in which extends the shank 65 of a bearing 66 carrying a friction roller 67 adapted to be engaged by the inclined portion 33 of the bottom of the combination float and reservoir 25. A set screw 68 screws in the socket 64 against the shank 65 to secure the latter in place after the same has been adjusted up or down to move the friction roller 67 in proper position relative to the inclined portion 33. When the combination float and reservoir 25 is in the normal position shown in Fig. 1 then the friction roller 67 is at the upper end of the inclined bottom portion 33 and consequently the lever 61 bears by its fork 60 on the free end of the lever 54 whereby the latter holds the valve 51 firmly to its seat 50 thus shutting off the water supply at this point. When 90 the combination float and reservoir 25 is tilted, as shown in Fig. 3, then the inclined bottom portion 33 moves out of engagement with the friction roller 67, and the pressure of the water in the water supply pipe 42 now opens the valve 51 to allow the water to flow from the water supply pipe 42 through the valve seat 50 into the valve casing 41 and from the latter by way of the spout 40 to the reservoir 31. The 100 water flowing into this reservoir 31 overflows the latter when in tilted position and refills the tank 10, and in doing so the rising water engaging the float 30 causes the combined float and reservoir 25 to swing back into its normal position, as shown in Fig. 3. When this takes place the friction roller 67 is reengaged by the inclined bottom 105 33 and consequently a swinging motion is given to the lever 61 which by the fork 110 60 bears down on the lever 54 whereby the valve 51 is moved into closed position to shut off the water supply.
- In order to swing the combined float and reservoir 25 from the normal position, shown 115 in Fig. 1, into dumping position, shown in Fig. 3, the following arrangement is made: The front of the tank 10 is provided with a bearing 70 (see Fig. 2) in which is mounted to turn a shaft 71 provided at its outer end with a suitable handle 72 under the control of the user of the water closet to impart a turning motion to the shaft 71. The inner end of the shaft 71 is provided with an arm 73 extending from the shaft 71 in opposite 120 directions and provided at its ends with friction rollers 74 and 75 normally bearing on the top of the front wall of the combined float and reservoir 25 directly above the inclined bottom 33 and to one side of the ful-
- 130

crum rod 27. On turning the shaft 71 in either direction the corresponding friction roller 74 or 75 bears on the front wall of the combined float and reservoir 25 thus imparting a swinging motion to the combined float and reservoir to tilt the latter until it reaches the position shown in Fig. 3. When the combined float and reservoir 25 is in this tilted position the inclined bottom portion 33 is inclined downwardly from the straight bottom portion 32 so that the water contained in the reservoir 41 readily flows out of the same.

It is expressly understood that the float 30 is an integral part of the reservoir 31 and is in the form of a hollow body completely air and watertight.

The operation is as follows:

When the several parts are in the position shown in Figs. 1, 2, 4 and 5 then the valve 51 is held in closed position, the reservoir 31 is filled with water and the tank 10 is filled with water, the level of which is at the top of the siphon 12. Now when the operator swings the handle 72 to one side and gives a quarter turn to the shaft 71 then the corresponding friction roller 74 or 75 of this arm imparts a swinging motion to the combined float and reservoir 25 and swings the latter into the tilted position shown in Fig. 3. The combined float and reservoir 25 when swung into this tilted position discharges its contents over the inclined bottom 33 into the tank 10 thus raising the level of the water contained therein to a distance above the siphon 12 whereby the latter is started and the water is rapidly sucked out of the tank 10 by way of the siphon and discharged into the water bowl 40 by way of the outlet, as previously explained. The water is drawn out of the tank 10 very quickly and far faster than the flow of the water through the upright small spout 40, and when the water has fallen to the level 45 of the foot 15 of the inlet leg 13 of the siphon 12 then the siphoning action is broken and further outflow of the water from the tank 10 ceases. By reference to the drawings it will be noticed that the wall of the 50 outlet opening 22 is spaced from the walls of the foot 20 of the outlet leg 14 and hence when the siphon is in action and the water rushes down the outlet leg 14 into the horizontal foot 20 then it rushes into the outlet 55 pipe 24 from all sides and consequently an exceedingly strong siphoning action is had as the water readily flows through this pipe 24 and down the same. It will also be noticed that the inlet openings 16 for the foot 60 15 of the inlet leg 13 of the siphon 12 is exceedingly large to insure a rapid outflow of the water from the tank. By experiments I have found that in making the legs 13 and 14 tapering as described proper and force- 65 ful siphoning action is obtained.

When the combined float and reservoir 25 swings into the tilted position mentioned and shown in Fig. 3 then the friction roller 67 is released and with it the levers 61 and 54 to allow the pressure of the water against the under side of the valve 51 to raise the latter thus permitting the latter to flow from the supply pipe 42 by way of the open valve seat 60, valve casing 41 and spout 40 into the reservoir 31. The water flows out 70 of this reservoir 31 into the tank 10 and refills the same, and as the water rises in the tank 10 it finally engages the float 30 thus causing an upward movement of the same to return the combined float and reservoir 25 80 to normal position at the time the tank 10 is filled, with the level of the water therein flush with the top of the siphon and with the reservoir 31 filled with water. When the combined float and reservoir reaches its 85 normal position the valve 51 is moved back onto its seat 50 thus shutting off the water supply. A small aperture 80 connects the interior of the foot 20 of the outlet leg 14 of the siphon 12 with the lower end of the 90 passage 43 to allow the small amount of water contained within the passage 43 to flow by way of the aperture 80 into the foot 20 and from the latter by way of the pipe 24 into the bowl to fill the latter. 95 It will also be noticed that when the combined float and reservoir 25 is swung from the normal position into dumping position then water is supplied to the tank by the combined float and reservoir 25 and through 100 the supply pipe 42 and at the same time the downward moving float 34 displaces water in the tank whereby the level of the water in the tank is raised quickly and a considerable distance to insure a quick and forceful start- 105 ing of the siphon.

It is understood that when the valve 51 is open, as previously explained, a portion of the water passing into the casing 41 passes by way of the apertures 49 into the 110 passage 43 to fill the same and this amount of water is utilized for refilling the bowl after the same has been flushed.

It will be noticed that by the arrangement described the metal valve casing 41 and its 115 valve 51 and the operating mechanism thereof is located above the level of the water in the tank 10 and consequently is not subjected to the corrosive action of the water. It will also be noticed that the 120 siphon 12 is an integral part of the tank 10 and is made of the same vitreous material of which the tank 10 is made and consequently is not liable to the corrosive action of the water; in fact, the many metallic 125 fixtures now generally employed in flushing apparatus of this character, such as supply and flush valves, metallic siphons, overflows, feed and refill pipes, rubber ball valves, floats, leather valves, rubber valve seats and 130

the like, are completely dispensed with and the flushing apparatus is composed of comparatively few parts not liable easily to get out of order.

5 Although the siphon 12 is shown in the drawings as an integral part of the back and bottom of the tank it obviously may be made an integral part of the front or either side of the tank, and hence I do not limit 10 myself to the construction disclosed. But it should be noted that whether the siphon structure is integral with the front or either side of the tank it defines substantially a chamber in which the combined float and 15 reservoir swings and is maintained.

Having thus described my invention, I claim as new and desire to secure by Letters Patent:—

1. A flushing apparatus for water closets 20 and other fixtures, comprising a tank of a vitreous material, and a siphon within the tank and formed integral therewith, the legs of the siphon being approximately rectangular in cross section, the inlet leg having an 25 integral flat foot provided with openings leading into the tank, the outlet leg having an integral foot provided at the bottom with an outlet.

2. A flushing apparatus for water closets 30 and other fixtures, comprising a tank of a vitreous material, and a siphon within the tank and formed integral therewith, the legs of the siphon being approximately rectangular in cross section, the inlet leg having 35 an integral flat foot provided with openings leading into the tank, the outlet leg having an integral foot provided at the bottom with an outlet having its wall spaced from the side walls of the foot.

40 3. A flushing apparatus for water closets and other fixtures, comprising a tank of a vitreous material, and a siphon within the tank and formed integral therewith, the legs of the siphon being approximately rectangular in cross section, the inlet leg having an 45 integral flat foot provided in the side and front walls with large inlet openings.

4. A flushing apparatus for water closets 50 and other fixtures, comprising a tank of a vitreous material, and a siphon within the tank and formed integral therewith, the legs of the siphon being approximately rectangular in cross section, the inlet leg having an 55 integral flat foot provided in the side and front walls with large inlet openings and at the top with small apertures.

5. A flushing apparatus for water closets 60 and other fixtures, comprising a tank of vitreous material and provided with an integral upright tubular passage extending through the bottom of the tank, a water supply pipe extending through the said passage, a valve casing fitting on the upper ends of the said passage and pipe and provided with 65 an outlet spout, the said valve casing being

connected with the said passage, and a siphon in the said tank and having the terminal of its outlet leg connected with the said passage and with a valve seat in register with the pipe and a valve mounted in the 70 said valve casing and controlling the said valve seat.

6. A flushing apparatus for water closets and other fixtures, provided with a combined float and reservoir made of a single piece of 75 vitreous material and mounted to swing in a tank, the reservoir having a bottom, a portion of which is approximately at a right angle to the side walls and the remaining portion is inclined upwardly and forms the 80 top for the float.

7. A flushing apparatus for water closets and other fixtures, provided with a combined float and reservoir made of a single piece of vitreous material, the reservoir having 85 a portion of its bottom inclined upwardly and forming the top of the float, the lower portion of which extends below the bottom of the reservoir.

8. A flushing apparatus for water closets 90 and other fixtures provided with a combined float and reservoir made of a single piece of vitreous material and mounted to swing in a tank, the reservoir having a bottom, a portion of which is approximately at a right 95 angle to the side walls and the remaining portion is inclined upwardly and forms the top of the float, the bottom portion of the float extending below the approximately right angle portion of the reservoir.

9. A flushing apparatus for water closets and other fixtures, comprising a tank of vitreous material, a siphon within the tank and integral therewith, the siphon having 100 its inlet and outlet legs provided with feet of 105 which the foot of the inlet leg is provided with inlet openings leading into the tank, and the foot of the outlet leg is provided with an outlet opening extending through the bottom of the tank, a combined float and 110 reservoir of vitreous material mounted to swing in the upper portion of the tank, a tubular passage rising in the tank and integral with the tank bottom and back and with one side of the siphon, a water supply 115 pipe extending in the said passage, a valve casing on top of the said passage and tube and provided with an outlet spout opening into the said reservoir, a valve in the said valve casing and controlling the flow of the 120 water through the said supply pipe, means controlling the said valve from the said combined float and reservoir, and manually controlled actuating means engaging the said combined float and reservoir to tilt the same. 125

10. A flushing apparatus for water closets and other fixtures, comprising a tank of vitreous material, a siphon within the tank and integral therewith, the siphon having its 130 inlet and outlet legs provided with feet, of

which the foot of the inlet leg is provided with inlet openings leading into the tank and the foot of the outlet leg is provided with an outlet opening extending through the bottom 5 of the tank, a combined float and reservoir of vitreous material mounted to swing in the upper portion of the tank, a tubular passage rising in the tank and integral with the tank bottom and back, and with one side 10 of the siphon, a water supply pipe extending in the said passage, a valve casing on top of the said passage and tube and provided with an outlet spout opening into the said reservoir, a valve in the said valve casing 15 and controlling the flow of the water through the said supply pipe, an arm engaging the said valve, a lever fulcrumed in the tank and supporting at one end the said arm, the other end of the lever being provided with a friction 20 roller adapted to engage the said combined float and reservoir, and a shaft journaled in the said tank and provided at its outer end with a handle and at its inner end with an arm having friction rollers at its 25 ends, either friction roller being adapted to engage the said combined float and reservoir to tilt the latter on turning the shaft in either direction.

11. A flushing apparatus for water closets 30 and other fixtures, comprising a tank of

vitreous material, a siphon within the tank and integral therewith, the siphon having its inlet and outlet legs provided with feet, of which the foot of the inlet leg is provided with inlet openings leading into the tank 35 and the foot of the outlet leg is provided with an outlet opening extending through the bottom of the tank, a combined float and reservoir of vitreous material mounted to swing in the upper portion of the tank, a 40 tubular passage rising in the tank and integral with the tank bottom and back and with one side of the siphon, a water supply pipe extending in the said passage and tube and provided with an outlet spout opening into 45 the said reservoir, a valve in the said valve casing and controlling the flow of the water through the said supply pipe, means controlling the said valve from the said combined float and reservoir, manually controlled actuating means engaging the said combined float and reservoir to tilt the same, and a refill and air supply opening connecting the outlet leg of the siphon with the said passage. 50
